UNITED STATES PATENT OFFICE.

ALBERT W. PEARSALL, OF NEW YORK, N. Y., ASSIGNOR TO THE METEOR DESPATCH COMPANY, OF PORTLAND, MAINE.

PNEUMATIC-DESPATCH-TUBE SYSTEM.

SPECIFICATION forming part of Letters Patent No. 582,829, dated May 18, 1897.

Application filed January 9, 1896. Serial No. 574,898. (No model.)

To all whom it may concern:

Be it known that I, ALBERT W. PEARSALL, of New York, county of New York, and State of New York, have invented new and useful

5 Improvements in Pneumatic-Despatch-Tube Systems, of which the following is a specification; and I hereby declare that the following is a full, clear, and exact description of the invention, which will enable others skilled 10 in the art to which it appertains to make and use the same.

My invention relates to new and useful improvements in pneumatic-despatch-tube systems in which pressure behind the carriers 15 is used to despatch the same from one part of the system to the other, in distinction from vacuum systems in which carriers are drawn along by the vacuum created in front thereof.

20 My invention especially relates to a system in which the air-pressure is started into circulation upon the insertion of a carrier into the tubes, as normally there is no circulation of pressure through said system. By such an arrangement there is a great saving of power 25 over systems in which the circuit is always open and the pressure constantly passing through the tubes, whether the carriers are being transmitted or not.

One object of my invention is to produce 30 a system in which pressure is introduced into the transmitting-tubes of the system upon the insertion of a carrier.

Another object is to produce a system in which, upon the arrival of the carrier at its 35 destination, the pressure which has driven said carrier from the starting-point to its destination is cut off upon the discharge of said carrier.

These and other objects are accomplished 40 by the mechanism hereinafter described, and shown in the drawings.

My invention consists of certain novel features hereinafter described, and particularly pointed out in the claims.

45 In the accompanying drawings, which illustrate a construction embodying my invention, Figure 1 is a side elevation of a pneumatic-despatch-tube system showing the salesmen's and cashier's stations, with certain parts of said stations in section. Fig. 2 50 is a detail view hereinafter described. Fig. 3

is a plan view of a cashier's station. Fig. 4 is an end view of a cashier's station. Fig. 5 is a detail view of the regulating device hereinafter described.

55

Like letters of reference refer to like parts throughout the several views.

From the cashier's station A there extends a line of tube B to the terminal C, located at the salesman's station D. At the cashier's 60 station there is provided a despatch-box E, having an open-ended collar E', through which the carrier is inserted into the despatch-box to be sent to the salesman's station D. The collar E' is partially closed at the 65 top, upon the insertion of the carrier, by the cover E⁹, secured to the lever E², pivoted at E³ between the lugs E⁴, secured to the outside of the collar E', and said lever, to the rear of its pivot-point E³ is provided with a 70 cam-surface E⁵, and at its forward end is provided with a finger-catch E⁶ and a projection E⁷. At the lower end of the despatch-box E, and in communication therewith by means of the narrow passage F', is a chamber F, 75 closed to the atmosphere by a flexible diaphragm F², secured in place by a metallic rim F³. To the center of this flexible diaphragm is an arm F⁴, to which the vertical lever F⁵ is pivoted at F⁶, and said lever extends upwardly through the flange E⁸ of the collar E', and near its upper end is provided with a hub F⁷, journaled on the pin F⁸, mounted in the lugs F⁹, secured to the side of the despatch-box E, and at its upper end 80 said lever has a dog F¹⁰, which is adapted, as will be hereinafter explained, to engage with the projection E⁷ of the lever E² and hold the said lever down and the cover closed when a carrier is being transmitted through the system.

On the same side of the despatch-box E as the lever F⁵ there is a lug G, to which is secured a flat spring G' by a suitable screw G², and said spring extends upwardly through a suitable bearing in the base-plate E⁸, and its upper end bears against the dog F¹⁰ on the upper end of the lever F⁵ and tends to hold said dog F¹⁰ outward, and the lower end, to which is secured the arm F⁴, with the flexible diaphragm F², inward, as shown in full lines, 95 Fig. 1.

H represents a regulating device, (shown

in detail in Fig. 5,) and it consists of a lever H', pivoted in the lug II², extending from the side of the despatch-box E, (see Fig. 5,) and through the short end II³ of said lever there extends a thumb-screw H⁴, with its inner end bearing against the side of the despatch-box, while the end H⁵ bears against the flat spring G'. In order to increase the tension of said spring G' against the upper end of the lever 10 F⁵ and create a greater inward pressure on the flexible diaphragm II², the thumb-screw H⁴ is screwed up tightly, thus bringing out the short end H³ and moving the long end H⁵ inwardly against the flat spring G', and thus 15 increasing the pressure of the spring against the upper end of the lever F⁵, or if it is desired to decrease the pressure of said spring on said lever the thumb-screw is unscrewed, thereby moving the short end H³ inwardly 20 and the long end H⁵ outwardly, thereby reducing the pressure on said flat spring G' of said long end H⁵ and the pressure of the spring G' against the upper end of the lever F⁵, for a purpose to be hereinafter described. In 25 order to hold the regulating device II in its adjusting position, a locking-disk II⁶ is provided, which is adapted to be screwed down on the lever H', as shown in Fig. 5, and thus holds the thumb-screw in its adjusted position.

30 Within the despatch-box E is a valve J, pivoted at J' and normally across the opening of the passage J² into the despatch-box E. The said passage J² communicates at its other end with an auxiliary reservoir K, at the lower 35 end of which the lever K' is pivoted at K², and to said lever there is secured the valve K³, which normally closes the opening of the passage J² into the auxiliary reservoir K. The upper end of the lever K' is provided with a 40 slot K⁴, and in said slot there is located a pin K⁵ on the end of the rod K⁶, which passes through a boss K⁷ in the flat side of the auxiliary reservoir K, and around said rod K⁶ there is a spring K⁸, resting at its opposite 45 ends against the boss K⁷ and head K⁹ of the said rod, and the tension of said spring is exerted to hold said rod outwardly, as shown in full lines, Fig. 1, and thus to hold the valve K³ closed and the lever E² and cover E⁹ in 50 their open positions, as shown in full lines, Fig. 1. The said auxiliary reservoir K receives its air-supply through the pipe L, which is in communication with an air-reservoir L'.

The tube B, connected to the bottom of the 55 despatch-box E, extends to the terminal C at the salesman's station D. The said terminal C consists of flat sides C³ with an outer curved guiding-plate C' and an inner curved guiding-plate C², and between said plates C' and C² 60 the carrier passes when received from the tube B, and at the extreme inner end of said guiding-plate C² guide-rods C⁴ are secured, and this arrangement permits the pressure passing around between the inner and outer 65 plates C' and C² to pass between and around the rods C⁴ to the outlet-tube M, but at the same time the said guide-rods C⁴ guide the

carrier to the outlet of the terminal, which is closed by the valve C⁵. This valve consists of two leaves C⁶ and C⁷, joined together by a suitable connecting-rod C⁸, and said valve C⁵ is pivoted to the terminal at C⁹, the area of the leaf C⁷ exposed to the pressure in the system being greater than the area of the leaf C⁶ exposed to the same pressure. The said valve C⁵ is held in this closed position, as shown in full lines, Fig. 1, by the pressure in the system, and the momentum of the discharged carrier is sufficient to open the valve C⁵ to permit the discharge of the carrier, and 75 instantly upon the said discharge the pressure on the larger leaf C⁷ closes the valve and holds it in a closed position, as shown.

The valve C⁵ is substantially of a construction and operates substantially the same as 85 the pressure-valve shown, described, and claimed in Letters Patent No. 527,073, dated October 9, 1894, and granted to the Meteor Despatch Company, of Maine, as my assignee.

When it is desired to send a carrier from 90 the cashier's station A to the salesman's station D, the operator places a carrier through the collar E' into the despatch-box E and then pulls down the lever E², and in said movement of the lever and the closing of the cover E⁹ 95 the cam-face E⁵ operates against the head K⁹ of the rod K⁶ and pushes said rod inwardly against the tension of the spring K⁸, so that the pin K⁵ acts on the lever K' and moves said lever, with the valve K³ secured thereto, 100 backward to the position shown in dotted lines, Fig. 1, and thus opens the passage J² to the air-pressure in the auxiliary reservoir K. The air passes through the passage J² into the despatch-box E and raises said valve 105 J upwardly to the position shown in dotted lines, Fig. 1, and thus closes and prevents any escape of the air up through the collar E', and the pressure acting on the carrier drives the same through the tube B to the 110 terminal C, where it is discharged as above described. If it were not for this valve J, as the pressure passed into the despatch-box E it would act on the under side of the cover E⁹ and create such a friction between the projection E⁷ on the lever E² and the dog F¹⁰ as 115 to prevent the proper working of the lever E², lever F⁵, and diaphragm F². By means of the valve J there is practically no pressure on the under side of the cover E⁹ and said cover acts more as a rest for the lever E² than to prevent the escape of the air. Immediately upon the passage of the air into the despatch-box E the said pressure acts on the flexible diaphragm F² and moves the same outwardly 120 with the lever F⁵, the upper end of which moves inwardly, and the dog F¹⁰ engages with the projection E⁷ on the lever E² and holds said lever down and said cover in a closed position, as shown in dotted lines, Fig. 1.

130 After the carrier has been inserted into the despatch-box and the lid closed it is driven through the system, as above described, and the carrier on reaching the terminal C opens

- the valve C⁵ and is discharged; but in the opening of the said valve to allow the discharge of the carrier a large opening is provided for the escape of the pressure in the system, whereby the back pressure is immediately affected and reduced throughout the line, so that the diaphragm F² and lever F⁵, owing to the reduction of pressure in the system, return to their normal positions, as shown in full lines, Fig. 1, and at the same time the lever E² is released from engagement with the dog F¹⁰ and the lever F⁵, and immediately the lever and the cover fly upward and uncover the opening to the despatch-box E, as the tendency of the rod K⁶, owing to the tension of the spring K⁸, is to hold the lever E² in a raised position. From this it will be seen that immediately upon the discharge of the carrier the back pressure in the line is so reduced as to permit the automatic release of the lever E² from engagement with the lever F⁵, and as said lever rises, owing to the movement of the rod K⁶ against the cam-face E⁵ of said lever, the valve K³ is closed by reason of the tension of the spring K⁸ on the rod K⁶ moving said rod outwardly and raising the lever E², as described, so that in the one movement, owing to the tension of the spring K⁸, the rod K⁶ raises the lever E² and cover E⁹, and at the same time closes the valve K³ and thus shuts off the pressure from the system. Upon the closing of the valve K³, the pressure being cut off from the despatch-box E through the passage J², the valve J drops to its normal position, as shown in full lines, Fig. 1, and the line is open and ready for insertion and transmission of another carrier from the salesman to the cashier, and the operation is repeated, as above described.
- The pressure throughout the tube varies in different systems, sometimes being ten ounces to the square inch and sometimes fifteen ounces to the square inch. Therefore the pressure on the flexible diaphragm F² varies; but at all times it is necessary to have sufficient pressure on the flexible diaphragm F² to hold the dog F¹⁰ of the lever F⁵ in engagement with the projection E⁷ of the lever E² upon the insertion and transmission of a carrier, the lever being moved by the hand, but the action of the pressure is so quick that the engagement of the dog F¹⁰ with the projection E⁷ is almost instantaneous with the insertion of a carrier, the downward movement of the lever, and closing of the cover, and in order to have this immediate action it is necessary that there should always be sufficient pressure in the system to act on the diaphragm F² and overcome the tension of the spring G¹, so as to cause the immediate engagement of the dog F¹⁰ with the projection E⁷ of the lever E².
- In order to regulate the proper amount of pressure on the diaphragm F², I have provided the regulating device H, previously referred to. If the internal pressure in the system on the diaphragm F² is high, the thumb-screw H⁴ would be screwed inwardly,
- so as to move the end H⁵ inwardly against the spring G¹ and thereby increase the tension of the spring G¹ against the upper end 70 of the lever F⁵, so as to counterbalance the high pressure in the system. When the pressure in the line is reduced by the delivery of a carrier at the terminal C, the lever F⁵ will return to its normal position owing to the reduction of pressure in the system by the escape of pressure at the terminal and by the tension of the spring G¹ against the upper 75 end of the lever F⁵, thereby allowing the release of the lever E², which in opening, by 80 reason of the rod K⁶, as above described, shuts off the pressure from the line by the closing of the valve K³. In the absence of this regulating device it will be obvious that if the pressure is high in the system the discharge of the carrier at the terminal C may not provide sufficient escape of the pressure in the line as to reduce the back pressure sufficiently to allow the return of the flexible diaphragm F² and the lever F⁵ to their normal positions in order to release the lever E² from engagement with the dog F¹⁰ on said lever F⁵. On the other hand, if the pressure in the system is low, it is obvious that the tension of the spring G¹ against the upper 95 end of the lever F⁵ must be reduced, so that the tension of said spring acting on the lever F⁵ and diaphragm F² would not exert too much pressure, so as to hold said diaphragm inwardly, as shown in full lines, Fig. 1, 100 against the pressure in the system and at the same time to keep the dog F¹⁰ from engagement with the projection E⁷ on the cover E². In such cases of low pressure the thumb-screw H⁴ is screwed outwardly, so as to allow the 105 end H⁵ to move outwardly and thus reduce the tension of the spring G¹ against the upper end of the lever F⁵.
- From the above it will be seen that the regulating device H is for the purpose of adjusting the tension of the spring G¹ on the lever F⁵ and the diaphragm F² to meet the varying pressures in the system—that is, when the pressure in the system is high the regulating device increases the tension of the 110 spring G¹ on the lever F⁵ and diaphragm F², but when the pressure in the system is low the regulating device H reduces the tension of the spring G¹ on the lever F⁵ and diaphragm F², so that in all cases said regulating device adjusts the tension of the spring G¹ on the lever F⁵ and diaphragm F², so that upon the discharge of the carrier from the terminal C the escape of pressure from the system through the opening caused by the 115 opening of the valve C⁵ is sufficient to reduce the back pressure in the system to such an extent as to allow the lever F⁵, owing to the pressure of the spring G¹, to move the diaphragm F² inwardly, as shown in full lines, 120 Fig. 1, and thereby to permit the release of the dog F¹⁰ and the upward movement of the lever E².
- To the end of the short tube M, I have se-

cured a windgate M' , which consists of an outer cylinder M^2 , provided with an opening M^3 , and within said cylinder M^2 there is arranged another cylinder M^4 , provided with an opening M^5 , adapted to register with the opening M^3 of the outer cylinder M^2 , and secured to the bottom of said inner cylinder M^4 is a shaft M^6 , by means of which the inner cylinder can be revolved to adjust the opening M^5 5 in relation to the opening M^3 of the outer cylinder M^2 . The object of this windgate on the end of the line is for the purpose of regulating the amount of back pressure in the line, as such back pressure is necessary in the 10 working of the system—that is, it is necessary to have sufficient back pressure in the despatch-box E to force the diaphragm F^2 out, as shown in dotted lines, Fig. 1, upon the insertion of a carrier. Now if the tube M was 15 freely open to the atmosphere there would not be enough back pressure in the despatch-box to hold the diaphragm F^2 out and the lever E^2 held down by engagement of the dog F^{10} with the projection E^7 on said lever. Therefore 20 said windgate is for the purpose of regulating the back pressure in the line so as to have the proper amount of back pressure in the system, and this will vary on different systems. For instance, if there was a long line 25 less back pressure would be required than on a short line. Consequently the inner cylinder M^4 would be turned so as to register the openings M^5 and M^3 and allow an escape of the pressure in the line; but on short lines the 30 openings M^5 and M^3 would not be brought into such full registration as on long lines, but the inner cylinder M^4 would be turned so as to allow a smaller escape of pressure than on long lines, as in long lines there is a certain amount of friction, which of itself creates 35 a certain amount of back pressure, so that for varying lines in order to regulate the amount of back pressure the inner cylinder M^4 is adjusted to bring its opening M^5 into proper relation with the opening M^3 of the outer cylinder M^2 , and in long lines it is so adjusted as 40 to allow a larger escape of air than in short lines. 45

From the above it will be seen that the wingate M' is for the purpose of reducing or increasing the back pressure in the system sufficiently to admit of the proper operation of the lever F^5 , diaphragm F^2 , and dog F^{10} in relation to the lever E^2 , in addition to the back pressure exerted by the carriers, which, due to the varying loads which they may have, would not in itself be sufficient to make the above-mentioned parts work with a sufficient degree of certainty. It is intended that sufficient back pressure be exerted by the regulation of the windgate to hold the diaphragm F^2 , lever F^5 , and dog F^{10} in such position as to prevent the lever E^2 , when moved to the position shown in dotted lines, Fig. 1, 60 from being released from engagement with the dog F^{10} , even if there are no carriers introduced into the system. By this arrange- 65

ment it is provided that the lever E^2 cannot be disengaged from the dog F^{10} except by the delivery of a carrier at the salesman's station, 7 whatever may be the weight of the carrier or the size of the felt heads, which become worn from use and admit of the escape of air. 7

I do not limit myself to the arrangement and construction shown, as the same may be varied without departing from the spirit of my invention. 7

Having thus ascertained the nature and set forth the construction of my invention, what I claim as new, and desire to secure by Letters Patent of the United States, is—

1. In a pneumatic-despatch-tube system, a carrier-transmitting tube having an inlet and an outlet for the carriers, an air-inlet, a valve normally closing said air-inlet, mechanism for opening said valve, and a locking device connected with said tube and by the pressure of air therein being caused to engage with said valve-opening mechanism to hold said valve in an open position. 8

2. In a pneumatic-despatch-tube system, a carrier-transmitting tube having an inlet and an outlet for the carriers, an air-inlet, a valve normally closing said air-inlet, mechanism for opening said valve, a locking device connected with said tube and by the pressure of air therein being caused to engage with said valve-opening mechanism to hold said valve open, an air-outlet, and means for controlling the passage of air through said air-outlet. 9

3. In a pneumatic-despatch-tube system, a carrier-transmitting tube having an inlet and an outlet for carriers, an air-inlet, a valve normally closing said air-inlet, mechanism for opening said valve to permit the passage of air through said air-inlet, and a locking device connected with said transmitting-tube and operated by the pressure of air therein adapted to engage with said mechanism to hold said valve open until the pressure of air in the said transmitting-tube is reduced to such an extent as to cause said locking device to release said mechanism. 10

4. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage at one end with said mechanism for holding said valve open and connected at its other end to a flexible diaphragm exposed to the pressure in the said transmitting-tube admitted through said air-inlet upon the operation of said mechanism, and means bearing on said locking device to cause the end connected to said diaphragm to exert a pressure on said diaphragm against the pressure in the said transmitting-tube. 12

5. In a pneumatic-despatch-tube system, a carrier-transmitting tube having an inlet and an outlet for the carriers, an air-inlet, a valve normally closing said air-inlet, mechanism for opening said valve to permit the passage of air

through said air-inlet, a locking device adapted to engage at one end with said mechanism for holding said valve open and connected at its other end to a flexible diaphragm exposed to the pressure in the said transmitting-tube admitted through said air-inlet upon the operation of said mechanism, and adjustable means bearing on said locking device to cause the end connected to said diaphragm to exert a pressure on said diaphragm against the pressure in the said transmitting-tube.

5 6. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage with said mechanism for holding said valve open and connected to a flexible 15 diaphragm exposed to the pressure in the said transmitting-tube admitted through said air-inlet upon the operation of said mechanism, and means bearing on said locking device to cause said locking device to exert a pressure 20 on said diaphragm against the pressure in the said transmitting-tube.

7. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage with said mechanism for holding said valve open and connected to a flexible 30 diaphragm exposed to the pressure in the said transmitting-tube admitted through said air-inlet upon the operation of said mechanism, and adjustable means bearing on said locking device to cause said locking device to exert a pressure 35 on said diaphragm against the pressure in the said transmitting-tube.

8. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage with said mechanism for holding said valve open and connected to a flexible 45 diaphragm exposed to the pressure in the said transmitting-tube admitted through said air-inlet upon the operation of said mechanism, and means bearing on said locking device to cause said locking device to exert a pressure on said 50 diaphragm against the pressure in the said transmitting-tube admitted through said air-inlet upon the operation of said mechanism, and means bearing on said locking device to cause said locking device to exert a pressure on said diaphragm against the pressure in the said transmitting-tube, an air-outlet, and means for controlling the escape of pressure through said outlet and thereby regulating the back pressure in the said transmitting-tube.

55 9. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage with said mechanism for holding said valve open and connected to a flexible 60

diaphragm exposed to the pressure in the said transmitting-tube admitted through said air-inlet upon the operation of said mechanism, 70 adjustable means bearing on said locking device to cause said locking device to exert a pressure on said diaphragm against the pressure in the said transmitting-tube, an air-outlet, and means for controlling the escape of 75 pressure through said outlet and thereby regulating the back pressure in the said transmitting-tube.

10. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, a locking device adapted to engage with said mechanism for holding 80 said valve open and connected to a flexible diaphragm exposed to the pressure in the said transmitting-tube admitted through said air-inlet upon the operation of said mechanism, adjustable means bearing on said locking device to cause said locking device to exert a pressure on said diaphragm against the pressure in the said transmitting-tube, an air-outlet, and adjustable means for controlling the escape of pressure through said outlet and 85 thereby regulating the back pressure in the said transmitting-tube.

11. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet into the system, a lever having a dog at its upper end adapted to engage with said mechanism for holding said 100 valve open and connected at its lower end to a flexible diaphragm exposed to the pressure in the said transmitting-tube admitted through said air-inlet upon the operation of said mechanism, a spring bearing against the upper end of said lever to cause the lower end of said lever to exert a pressure on the diaphragm against the pressure in the said transmitting-tube, and means for regulating the pressure exerted on the upper end of said lever by said spring.

12. In a pneumatic-despatch-tube system, a carrier-transmitting tube having an inlet and an outlet for the carriers, an air-inlet, a valve normally closing said air-inlet, mechanism for opening said valve to permit the passage of air through said air-inlet, and a locking device adapted to engage with said mechanism for holding said valve open by the pressure in the said transmitting-tube admitted through said 110 air-inlet upon the operation of said mechanism and adapted to be released from engagement with said mechanism upon the discharge of the carrier from the said outlet.

13. In a pneumatic-despatch-tube system, a carrier-transmitting tube having an inlet and an outlet for the carriers, an air-inlet, a valve normally closing said air-inlet, mechanism for opening said valve to permit the passage of air

through said air-inlet, a locking device adapted to engage with said mechanism for holding said valve open by the pressure in the said transmitting-tube admitted through said air-
5 inlet upon the operation of said mechanism and adapted to be released from engagement with said mechanism upon the discharge of the carrier from the said outlet, and a valve for said carrier-inlet normally open and
10 adapted to be closed by the pressure admitted through said air-inlet and adapted to return

to its normal position upon the discharge of the carrier from the said transmitting-tube.

In testimony whereof I have signed my name to this specification, in the presence of 15 two subscribing witnesses, on this 6th day of January, A. D. 1896.

ALBERT W. PEARSALL.
